(57) **CLAIM**

The ornamental design for a modular student desk, as shown and described.

DESCRIPTION

FIG. 1 is a top view of a modular student desk, showing my new design;

FIG. 2 is a front elevation view thereof;

FIG. 3 is a rear elevation view thereof;

FIG. 4 is a bottom view thereof; and,

FIG. 5 is a perspective view thereof.

The broken line portion of the figure drawings is included to show portions of the article that forms no part of the claimed design.
